UNITED STATES PATENT OFFICE.

GEORGE KENDALL PALMER, OF MIAMI, FLORIDA.

PROTECTING DEVICE FOR TOILET-SEATS.

1,237,548.

Specification of Letters Patent. Patented Aug. 21, 1917.

Application filed April 25, 1916. Serial No. 93,432.

To all whom it may concern:

Be it known that I, GEORGE K. PALMER, a subject of King George of Great Britain, residing at Miami, in the county of Dade and State of Florida, have invented new and useful Improvements in Protecting Devices for Toilet-Seats, of which the following is a specification.

This invention relates to a protecting device to be used in connection with toilet seats.

The primary object of the invention is to provide a device of this character in which the toilet is provided with a seat having connected therewith strips of material to serve as a shield, with the seat so constructed as to facilitate the passing of the strips over the seat when the occasion requires by mechanism for this purpose carried by a plate arranged in the rear of the seat and also serving as a support for spools upon which the used portions of the strips may be wound.

Another object of the invention is to provide the device with winding mechanism for said strips which may be arranged within convenient reach of the person occupying the seat and is so constructed as to permit the strips to be quickly and easily moved over the seat when desired.

With these and other objects in view, the invention resides in the novel combination and arrangement of parts, which will be hereinafter described and particularly pointed out in the claims.

The preferred embodiment of the invention has been illustrated in the accompanying drawing, although no restriction is necessarily made to the precise details of construction therein shown, as changes, alterations, and modifications within the scope of the claims may be resorted to when desired.

Like characters of reference denote corresponding parts throughout the several views in the drawing, in which:

Figure 1 is a side elevation of the device showing the same applied to the seat of a toilet and connected with a support.

Fig. 2 is a top plan view of Fig. 1.

Fig. 3 is a vertical longitudinal section on the line 3—3 of Fig. 2.

Fig. 4 is an enlarged detail sectional view through an end of one of the seat sections.

Fig. 5 is a perspective view of the yoke which forms a part of the toilet seat.

Fig. 6 is a perspective view of the brackets

and pin by means of which the seat is connected with the toilet.

Referring now to the drawing in detail, the numeral 1 designates a toilet hopper of the type now in common use and having connected therewith, the pipe of the flush tank (not shown in the drawings), said hopper being arranged adjacent a wall 2 with which is connected a plate supporting rolls of protective material and winding mechanism therefor, hereinafter described.

The hopper 1 is provided with a seat 3 having spaced seat sections 4 and 5, the opposite sides of which are recessed to provide an opening 6 and have connected therewith to extend beyond the seat sections ears 6'.

A yoke 7 forming a part of the seat 3 is interposed therebetween and the rim of the hopper, with the arms 8 of the yoke secured to the respective seat sections and connected by the cross bar 9 of the yoke which is arranged adjacent the rear of said seat and provided with ears 9' having passed therethrough a pin 9'' also passing through ears 10 at the ends of the cross bar 9 on the arms 8 and through brackets 10' on the rim of the hopper to hingedly connect the seat 3 therewith. The arms 8 are provided at their free ends with ears 11 which like the ears 10 aline with the ears 6' on the seat sections.

The pin 9'' has mounted thereon a pair of rollers 12 underlying the respective seat sections 4 and 5 and held in spaced relation by the ears 9' of the cross bar of the yoke, 90 said rollers 12 being in alinement with rollers 16 at the opposite ends of the seat sections and mounted to turn in the ears 6' on the yoke and seat sections.

The arms of the yoke have formed thereon lugs with which are connected buffers 16', which when the seat 3 is in lowered position contact with the rim of the hopper and space the arms of the yoke therefrom.

A plate 18 is secured to the wall 2 in the rear of the hopper 1 and is provided between its ends with spaced arms 19 below which are arranged spaced arms 20 of less length than the arms 19. A shaft 21 is mounted in ears 23 on the plate 18 below the arms 19, said shaft being provided at each end with a sprocket wheel 24.

A second shaft 25 is mounted in bearings 26 on the plate 18 above the arms 19 and has fixed to one end thereof a sprocket wheel 110

27 and at its other end a ratchet wheel 28 engaged by a spring pressed dog 29 on a ratchet lever 30 mounted to turn on the shaft 25. A sprocket chain 31 connects the 5 sprocket wheel 27 with one of the sprocket wheels 24 on the shaft 21.

Mounted to turn in the arms 19 is a shaft 33 provided with winding spools 34, said shaft being provided with a sprocket wheel 10 35 connected with the other sprocket wheel 24 on the shaft 21 by means of a sprocket chain 36. The sprocket wheels 35 and 24 being relatively small in comparison to the sprocket wheel 27 so that, when the lever 15 30 is moved upwardly and the shaft 25 rotated by means of the dog 29 the shaft 33 is rapidly rotated.

A shaft 37 is removably mounted on the arms 20 and is provided with disks 38 for 20 contact with the ends of rolls 39 of protective material, said material consisting preferably of strips of waxed paper and having ends initially carried upwardly and over the rollers 16 at the rear end of the seat sections, thence over the rollers at the forward 25 ends of the seat sections and beneath said seat sections and over the rollers 12 and connected therewith the winding spools 34.

With the strips of protective material arranged as above described, it will be seen that when the said strips have been used as a shield, upward movement upon the lever 30 will cause the shaft 33 to be rotated through its connection with the shaft 25 by 35 means of the sprocket chains 31 and 36 thus rotating the winding spools 34 and causing the used portion of the strips of protective material to be carried beneath the seat 3 as the strips are unwound from the rolls on 40 the shaft 37.

It will be noted with reference to the drawings, that the ears 9' and 10 on the bar 9 of the yoke serve as guides for the strips, so that the same are evenly wound 45 upon the winding spools 34 when unwound from the rolls on the shaft 37.

From the foregoing description, taken in connection with the accompanying drawings, it is at once apparent that a device of

the class described has been provided which 50 is simple in construction and highly efficient in use.

Having thus described the invention, what is claimed as new, is:

1. In a device of the class described, winding mechanism, a yoke swingingly connected with the hopper of a toilet, seat sections carried by the yoke, rollers at opposite ends of the seat sections, and rolls of protective material having portions thereof trained over 60 said seat sections and connected with the winding mechanism.

2. In a device of the class described, winding mechanism, a yoke, seat sections connected with the arms of the yoke, rollers carried by the yoke and seat sections and arranged at opposite ends thereof, a rod connecting said yoke with the hopper of a toilet and having rollers thereon underlying said seat sections, and rolls of protective 70 material having portions thereof trained over the rollers at the ends of the seat sections, the rollers on the rod, and connected with the winding mechanism.

3. In a device of the class described, 75 brackets for connection with the rim of the hopper of a toilet, a yoke having ears thereon alining with said brackets, a rod passing through said ears and brackets and having rollers thereon, spaced seat sections overlying said rollers and connected with the arms of the yoke, rollers at opposite ends of the seat sections, ears on the yoke and seat sections supporting the last mentioned rollers, a plate, winding spools connected with the 85 plate, rolls of protective material having connection with the plate and having portions thereof passing over the rollers at the ends of the seat sections, the rollers on the rod and connected with the winding spools, 90 and means on the plate connected with the winding spools for turning the same.

In testimony whereof I affix my signature in presence of two witnesses.

GEORGE KENDALL PALMER.
